The ornamental design for a bicycle seat with locking device, as shown and described.

DESCRIPTION

FIG. 1 is a left side view of a bicycle seat with locking device, showing my new design, with locking bars in a folded position;

FIG. 2 is a top view thereof;

FIG. 3 is a bottom view thereof;

FIG. 4 is a rear view thereof;

FIG. 5 is a front view thereof;

FIG. 6 is a right side view thereof;

FIG. 7 is a lower perspective view thereof;

FIG. 8 is an upper perspective view thereof;

FIG. 9 is a left side view of the bicycle seat with locking device in an alternative position with the locking bars in an extended position;

FIG. 10 is a top view thereof of the alternative position;

FIG. 11 is a bottom view thereof of the alternative position;

FIG. 12 is a front view thereof of the alternative position;

FIG. 13 is a rear view thereof of the alternative position;

FIG. 14 is a right side view thereof of the alternative position;

FIG. 15 is a lower perspective view thereof of the alternative position; and,

FIG. 16 is an upper perspective view thereof of the alternative position.

The nature and intended use of the article in which the design is embodied is that of a bicycle seat with extendable bars, useful for locking a bicycle.
